UNITED STATES PATENT OFFICE.

FRITZ WEVER AND KARL MAIER, OF STUTTGART, GERMANY.

SEWING AND TRIMMING MECHANISM.

No. 802,672.

Specification of Letters Patent.

Patented Oct. 24, 1905.

Application filed December 19, 1901. Serial No. 86,531.

To all whom it may concern:

Be it known that we, FRITZ WEVER and KARL MAIER, citizens of the German Empire, residing at Stuttgart, in the Kingdom of 5 Würtemberg, Germany, have invented certain new and useful Improvements in Sewing and Trimming Mechanism, of which the following is a description, reference being had to the accompanying drawings and to the letters 10 of reference marked thereon.

The present invention relates to an improvement in sewing-machines, and particularly to attachments for sewing-machines whose stitch-forming mechanism comprises devices for depositing a plurality of rows of loops upon opposite sides of a central line of feed, with cross-stitch devices therefor; and the invention has for its object to provide such machines with a mechanism whereby open or 15 filigree work may be produced upon a fabric sewed upon such a machine without the cloth being freed from the presser-foot before the cross-stitch is sewed.

The present invention consists, in combination with stitch-forming mechanism, of a reciprocating cutter arranged in advance thereof which cuts the cloth and a device provided with oppositely-turned folding-recesses at its rear end adjacent the needles and arranged to 20 fold and guide the edges of the opening made by the cutter into position within the space between the needles, whereby the stitch-forming mechanism will bind the raw upturned edges of the fabric and make the ornamental 25 stitching or open-work shown in the drawings.

The invention further consists in various matters hereinafter described and referred to in the appended claim.

The invention is illustrated in the accompanying drawings, in which—

Figure 1 is a perspective view of a portion of a machine provided with our invention. Fig. 2 is a side view, partly in section. Fig. 3 is a plan on the line A A of Fig. 2. Fig. 4 is a front view of Fig. 2. Fig. 5 is a side view showing one side of the cloth-guide cut away. Fig. 6 is a section on line B B of Fig. 2, illustrating the cloth guiding and hemming attachment in position between the arms of 50 the presser-foot.

In the drawings, *a* illustrates the needle-bar carrying a needle-clamp *b*, within which are fixed the needles. Said needle-clamp is provided in front with arms *a'*, between which

is clamped the upper end or shank of a cutting-blade *c*, the clamping means being, as shown, for example, a screw *b'*, which passes through both of the arms *a'*. The cutter *c* is longer than the needle, travels up and down with the needle-bar, and its free extremity 55 passes into a slot *d* in the throat-plate A. The presser-foot B is attached to the presser-bar C in the usual manner and has the usual openings for the passage of the two needles. It is bifurcated, as shown, to receive the attachment *f*, which extends beyond the forward edge of the throat-plate and is slotted to register with the slot *d* in said throat-plate 60 through this slot *g* in the attachment *f*, the knife reciprocating up and down. At its 65 rear end this attachment *f* is widened and is shown as secured to the presser-foot by the screw *h*, and each side is provided with in-turned wings *i*, forming recesses to fold and guide the raw edges of the fabric which has 70 been split by the cutter. The presser-foot is cut out in rear of its slot *m* at *l* and in front of the needle-openings to accommodate the widened portion of the attachment *f*, and the folding guiding portions of said attachment 75 *f* terminate at a point just in front of the needle-openings in the throat-plate, which register with the needle-openings in the presser-foot, and the width of said rear portion of the attachment *f* is slightly less than 80 the distance between the two outer edges of the needles, so that only the portion of the material lying between the edge of the fabric after it is severed by the knife and the needle 85 can be folded.

In operation a piece of fabric to be provided with the opening or filigree work is placed in the machine beneath the action of the presser-foot, and the knife first divides the material, and then the raw edges are 95 folded by the guiding-wings on either side at the rear of the attachment *f* and are fed to the stitch-forming mechanism, which, as herein shown, makes the cross-stitch illustrated in Fig. 1, the stitches securing and binding 100 the raw edges and making an ornamental open-work seam.

Any suitable form of cross-stitch mechanism may be provided; but, as herein shown, we prefer that in the well-known union special 105 type of twin-needle machine illustrated in Patent No. 344,493 of June 29, 1886.

Having thus described our invention, what

we claim as new, and desire to secure by Letters Patent, is—

In a sewing-machine having a trimming mechanism including a trimmer-knife, a
5 presser-foot having a bifurcated forward end, and an enlarged transverse opening in rear thereof, a slotted plate for the passage of the trimmer-knife, and having an enlarged rear end fitting the enlarged opening in the presser-
10 foot, said enlarged rear end having guiding-

scrolls for the severed fabric; substantially as described.

In testimony whereof we affix our signatures in presence of two witnesses.

FRITZ WEVER.
KARL MAIER.
